CLAIM

The ornamental design of a document holder for a display terminal, substantially as shown and described.

DESCRIPTION

FIG. 1 is a perspective view of a document holder for a display terminal showing our new design, the environmental structure shown in dotted lines being for illustrative purposes only and not a part of the design;

FIG. 2 is a left side elevational view thereof;

FIG. 3 is a front elevational view thereof;

FIG. 4 is a top plan view thereof; and

FIG. 5 is a rear elevational view thereof.

FIG. 1

FIG. 2

FIG. 3

FIG. 4

FIG. 5
